UNITED STATES PATENT OFFICE.

MARGERY N. LUDLOW, OF SARATOGA SPRINGS, NEW YORK.

GREASE-GUN FOR WHEEL-HUBS.

1,149,660.

Specification of Letters Patent.

Patented Aug. 10, 1915.

Application filed December 8, 1913. Serial No. 805,217.

To all whom it may concern:

Be it known that I, MARGERY N. LUDLOW, a citizen of the United States, residing at Saratoga Springs, county of Saratoga, and State of New York, have invented certain new and useful Improvements in Grease-Guns for Wheel-Hubs, of which the following is a specification.

The invention relates to such improvements and consists in the novel construction and combination of parts hereinafter described and subsequently claimed:

Reference may be had to the accompanying drawings, and the reference characters marked thereon, which form a part of this specification.

Similar characters refer to similar parts in the several figures therein.

Figure 1 of the drawings is a view in central longitudinal section of my improved grease-gun attached to the hub of an automobile-wheel in place of the hub-cap. Fig. 2 is a similar view of the wheel-hub with the hub-cap attached thereto. Fig. 3 is a view partly in side elevation and partly in central longitudinal section of the grease-gun detached from the hub. Fig. 4 is a similar view of the coupling-ring detached. Fig. 5 is a central longitudinal section of the barrel-cap of the grease-gun detached. Fig. 6 is a central longitudinal section of a grease-gun embodying my invention in modified form.

The principal object of the invention is to quickly and easily inject a filling of grease into the roller-bearing contained within the hub of an automobile-wheel.

Referring to the drawings wherein the invention is shown in preferred form, 1 is the hub of an ordinary automobile-wheel having an open screw-threaded end adapted to be closed by a hub-cap, 2, in the usual manner. Within the hub is a roller-bearing, 3, interposed between the hub and the axle, 4. The grease-gun comprises a barrel, 5, interiorly screw-threaded to fit the screw-threaded plunger or piston, 6, fixed upon a spindle, 7, which projects through the cap, 8, at the outer end of the barrel, having its projecting end provided with a handle, 9. The cap, 8, is detachably secured upon the outer end of the barrel by means of a pair of exteriorly projecting pins, 10, on the barrel which are adapted to be located in an annular interior groove, 11, in the flange of the cap. The pins, 10, enter the groove, 11, through lon-

gitudinal grooves, 12, as the cap is applied to the barrel by a bayonet movement. The inner end of the barrel is open and is screw-threaded at 13 to receive a similarly screw-threaded coupling-ring, 14, which coupling-ring is also screw-threaded at 15 to connect with the screw-threaded end of the hub, 1, in place of the hub-cap, 2. A plurality of coupling-rings, 14, can thus be made interchangeable to adapt the gun for connection with different hubs.

In using the device, the barrel-cap, 8, and the piston, 6, are removed from the barrel and the barrel is filled with grease. The piston and barrel-cap are then applied to the barrel, which is attached to the open end of the hub in place of the hub-cap which is temporarily removed. The axle may then be jacked up to raise the wheel from the floor or ground. The user then holds the handle, 9, of the gun against rotation, while the wheel is rotated or spun in a direction to screw the piston or plunger into the barrel, thus forcing the grease from the barrel into the hub, all of the open spaces within which may thus be completely filled with grease without danger of escape of the grease from the outer end of the hub. To permit of this manner of operation without danger of unscrewing the coupling-ring, 14, from either the hub or the barrel, all of the screw-threaded connections between the barrel, 5, and the plunger, 6, and ring, 14, are pitched in the same direction as the screw-threads on the hub, whereby said operation tends to tighten instead of to unscrew the gun from the hub. If desired the plunger, 16, and interior of the barrel, 17, may be made plain, and the spindle, 18, screw-threaded to fit a screw-threaded aperture in the barrel-cap, 19, as shown in Fig. 6, thus effecting a screw-threaded connection between the plunger and the barrel.

What I claim as new and desire to secure by Letters Patent is—

1. The combination with a wheel-hub having an open screw-threaded outer end adapted to receive a hub-cap; of a grease-gun having a screw-threaded open end adapted to fit said screw-threaded end of the hub interchangeably with the hub-cap.

2. In a device of the class described, and in combination, a barrel having a screw-threaded open end; a plunger within the barrel; means for forcing the plunger toward the open end of the barrel; and a

ring screw-threaded to fit the screw-threaded open end of the barrel and also screw-threaded to fit the screw-threaded open end of a wheel-hub interchangeably with the hub-cap.

3. The combination with a wheel-hub having an open screw-threaded outer end adapted to receive a screw-threaded hub-cap; of a grease-gun comprising a barrel having a screw-threaded open end adapted to fit said screw-threaded end of the hub interchange-

able with the hub-cap, a piston having a screw-threaded connection with the barrel pitched in the same direction as the screw-thread on the hub, and a handle for preventing rotation of said piston. 15

In testimony whereof, I have hereunto set my hand this 29 day of November 1913.

MARGERY N. LUDLOW.
